PIN HOLDER OR SIMILAR ARTICLE

Eldon P. Brautigam, Anchorage, Territory of Alaska

Application September 28, 1955, Serial No. 38,141

Fig. 1

Term of patent 7 years

(Cl. D86—10)

Figure 1 is a perspective view of a pin holder or similar article, showing my new design;

I claim:

The ornamental design for a pin holder or similar article, as shown.
